Specification for Design.

Patented Mar. 23, 1920.

Application filed June 13, 1919. Serial No. 304,065. Term of patent 14 years.

To all whom it may concern:

Be it known that I, WILLARD M. SMITH, a citizen of the United States of America, and a resident of the city of White Plains, in the county of Westchester and State of New York, have invented a new, original, and ornamental Design for Gloves, of which the following description, in connection with the accompanying drawing, is a specification.

In the drawing, Figure 1 represents the front side of a glove and Fig. 2 the back side of a glove showing my design.

I claim as my invention:

The ornamental design for a glove, as shown.

WILLARD M. SMITH.
